(57) **CLAIM**

I claim the ornamental design for an “ammunition box air compressor”, as shown.

DESCRIPTION

FIG. 1 is a perspective view of the ammunition box air compressor, showing the present invention.

FIG. 2 is a rear elevational view of the ammunition box air compressor of the invention.

FIG. 3 is a front elevational view of the ammunition box air compressor of the invention.

FIG. 4 is a left elevational view of the ammunition box air compressor of the invention.

FIG. 5 is a plan view of the ammunition box air compressor of the invention.

FIG. 6 is a right elevational view of the ammunition box air compressor of the invention; and,

FIG. 7 is a bottom view of the ammunition box air compressor of the invention.

In all views the top lid is shown in the open position.
